CLOSURE FOR RECEPTACLES

Charles Newman, New York, N. Y., and Walter O. Roach, South Bend, Ind., assignors, by mesne assignments, to Roach Appleton Manufacturing Company, South Bend, Ind., a corporation of Delaware

Application April 14, 1931, Serial No. 529,928

3 Claims. (Cl. 247—26)

The present invention relates to improvements in closures for receptacles.

More particularly, the present invention relates to improvements in closures for outlet boxes, outlet receptacles and other devices used in the protection of electric wiring or other electrical equipment. It has long been the practice to provide outlet boxes, outlet receptacles and the like with knock-outs, usually circular in outline, which, when removed from the outlet boxes, receptacles or the like, provide openings for the reception of armored cable. More recently, the knock-outs referred to have been replaced by closure members which may be pried outwardly of the box or receptacle.

The present invention relates in its more specific aspects to such closures, though, as the description proceeds, it will be apparent that the invention has a broader application.

20 In this specification, switch boxes, receptacles and other devices commonly provided with knock-outs or pry-outs will be referred to broadly as "receptacles."

An object of the present invention is to provide a receptacle having a readily removable closure which, when in closing position, is effective to prevent the passage of sparks or flame from the interior of the receptacle to the exterior thereof.

30 A further object is to provide an improved closure which, while tightly closing the opening with which it cooperates, is nevertheless readily removable by means of the tools with which artisans are commonly equipped.

35 A further object is to provide a closure which may be readily turned out of its operative relationship with the wall in which it is located, so that it may be readily manipulated by an artisan, either by his fingers or by means of a pair of pliers or the like, to remove said closure.

40 Further objects will appear as the description proceeds.

Referring to the drawing—

Figure 1 is a view in side elevation of a receptacle commonly known as a switch box, said receptacle being provided with closures embodying the principles of the present invention.

Figure 2 is an end view of the structure shown in Figure 1.

50 Figure 3 is a sectional view of part of the wall of a receptacle such as illustrated in Figures 1 and 2, Figure 3 being taken along the plane indicated by the arrows 3—3 of Figure 2; and

55 Figure 4 is a sectional view taken along the

planes indicated by the arrows 4—4 of Figure 2.

Numeral 10 indicates a receptacle which, in the illustrated embodiment of the present invention, is rectangular in shape. One or more of the walls of said receptacle 10 may be provided with removable closures, which removable closures are indicated by the numerals 11, 11. To accord with usual practice, said closures 11, 11 may be circular in outline and are, according to usual practice, integral with the wall with which they cooperate. Each of said closures 11 is defined by the perimeter of a circle or other geometrical figure, said circle or other geometrical figure defining a line of rupture or weakened material. Said line of rupture is indicated by the numeral 12 and, as clearly appears from the drawing, is interrupted at two substantially diametrically opposed regions by intact portions 13, 13, which intact portions are adapted to operate as hinges to permit the turning of the closure about the diameter which includes the points marking said intact portions. The line indicated by the numeral 14 indicates the diameter referred to, which diameter marks the axis about which the closure 11 is adapted to be turned. Each closure 11 may be provided with a small indentation or abutment upon the outer face thereof to provide a grip for the application of a screw driver or other tool. The indentations or abutments referred to are indicated by the numerals 15, 15, and are preferably located adjacent to the line of rupture 12 at regions displaced approximately 90° from the diameter 14.

As indicated above, the present invention contemplates a structure in which the closure 11 is turned about the diameter 14. Inasmuch as the wall of the receptacle 10 will have appreciable thickness, it may be preferred to swedge the closure 11 slightly so that it is curved relative to the axis 14. This structure is clearly indicated in Figures 3 and 4. By reason of the curvature referred to, the perimeter of the closure 11 is displaced a slight amount from the wall of the opening with which said closure 11 cooperates, whereby ease of swing of the closure 11 is had.

As is well known to those skilled in the art, switch boxes of the type shown in the drawing are commonly provided with clamping devices on the interior thereof for clamping the armored cable. In order that a minimum of interference may be had between the swinging closure 11 and the clamp, the axis which includes the points constituting the hinges 13, 13, 110

will be so disposed that a minimum amount of interference will be had during the swinging movement referred to. In Figure 2 the clamp is indicated in dotted lines by the numeral 16, 5 which clamp in certain positions is disposed in underlying relationship with certain of the closures 11. In the construction illustrated, the diameter 14, which includes the hinge points 13, 13, is disposed in normal relationship with 10 the clamping face of the clamp 16.

The mode of operation of the above-described embodiment of the present invention will be clear without detailed explanation. It may be stated, however, that the closures 11 when in 15 their operative positions provide complete or practically complete closures for their corresponding openings. When it is desired to remove one of the closures 11 to permit the mounting of armored cable, the closure 11 will 20 be struck on one side of the diameter 14 by means of a tool, such as a screw driver, the depression 15 providing a grip whereby an effective blow may be applied. Such a blow will 25 swing the closure 11 into angular relationship with the corresponding wall of the receptacle 10, whereby said closure may be readily gripped by the fingers of the artisan or by a pair of pliers or other tool in the hand of the artisan, whereby the closure may be readily broken away 30 from the remainder of the wall. Such an angular position of the closure 11 is indicated in the right-hand side of Figure 1.

Though a preferred embodiment of the invention has been described in detail, many mod- 35

ifications will occur to those skilled in the art and it is intended to cover all such modifications that fall within the scope of the appended claims.

What is claimed is:

1. A wall having a closure integral therewith, 80 said closure being defined by a geometrical figure interrupted by intact portions diametrically opposed to each other, said closure being curved about an axis which includes said intact portions to provide a slight amount of clearance between said closure and the remainder of said wall.

2. A wall having a closure integral therewith, 85 said closure being defined by a geometrical figure interrupted by intact portions diametrically opposed to each other, said closure being curved about an axis which includes said intact portions to provide a slight amount of clearance between said closure and the remainder of said wall, said closure being provided with a tool-gripping portion displaced from said axis. 95

3. A wall having a closure integral therewith, 100 said closure being defined by a geometrical figure interrupted by intact portions diametrically opposed to each other, said closure being curved about an axis which includes said intact portions to provide a slight amount of clearance between said closure and the remainder of said wall, said closure being provided 105 with tool-gripping portions displaced from said axis.
